UNITED STATES PATENT OFFICE

FRANK W. ANDREWS, OF DAYTON, OHIO, ASSIGNOR, BY MESNE ASSIGNMENTS, TO
FRIGIDAIRE CORPORATION, A CORPORATION OF DELAWARE

REFRIGERATING APPARATUS

Application filed April 28, 1927. Serial No. 187,355.

This invention relates to refrigerating apparatus of the compression type.

One of the objects of the invention is to charge refrigerant into a compression system, particularly under service conditions, in a simpler, and more reliable and more expeditious manner than has been done heretofore.

It is also one of the objects to construct the apparatus constituting a refrigerating system in such a manner as to facilitate the charging of refrigerant.

Still another object is to construct the apparatus so as to facilitate determination of the exhausting of the reserve supply of refrigerant.

Further objects and advantages of the present invention will be apparent from the following description, reference being had to the accompanying drawings, wherein a preferred form of embodiment of the present invention is clearly shown.

In the drawings:

Fig. 1 is a diagrammatic illustration of a refrigerating system showing a method of charging refrigerant.

Fig. 2 is a section thru a portion of the apparatus shown in Fig. 1.

The refrigerating system shown in the drawings comprises a compressor 20 driven by a motor 21 and connected to a condenser 22 which discharges into a receiver or reservoir 23 for liquid refrigerant, the bottom of which is connected thru a conduit 24 with an evaporator 25. The evaporator is connected to the intake side of the compressor thru a conduit 26. The evaporator is of the flooded type, having a valve operated by a float 27 for maintaining liquid refrigerant

supplied thru the conduit 24 at constant level. The compressor is operated in response to refrigerating demand thru the agency of any suitable automatic switch 30, which may be actuated by a pressure-responsive device 31 connected to the conduit 26. The apparatus thus far described is conventional and its particular construction forms no part of the present invention.

The system is designed to operate with a constant quantity of liquid refrigerant in the

evaporator (indicated by the lever 28) and with a certain reserve supply of liquid refrigerant in the reservoir 23, indicated for example, by the level 29. Due to various causes, for example leaks, the system may not contain enuf refrigerant. The condition of an insufficient quantity of refrigerant may be indicated in various ways, for example, by frequent starting and stopping, or by a hissing sound at the float valve, or by failure to refrigerate. It will be understood that the pressure within the condenser and receiver is high (for example it may be 50 pounds per square inch gauge) and therefore as long as there is any liquid in the receiver it will be forced into the conduit 24. If sufficient refrigerant has been lost from the system, the liquid level in the evaporator will not be high enuf to close the float valve and all of the liquid in the receiver will flow into the evaporator.

My invention provides means whereby refrigerant may be readily charged into the system. The conduit 24 is provided with two valves 35 and 36 and has a branch connection 37 containing a valve 38. The connection 37 is adapted to be connected to any suitable supply of liquid refrigerant 40. Preferably this is a container such as a steel bottle, inverted as shown in Fig. 1, and containing a quantity of liquid refrigerant 41 and a quantity of gaseous refrigerant 42. It will be understood that the refrigerant boils at a very low temperature, therefore a bottle containing liquid refrigerant at ordinary room temperature will be at high pressure. Thus at a temperature of 70° F., the pressure of the gaseous refrigerant may be 35 pounds per square inch.

When it is desired to charge refrigerant into such a system the container 40 is connected to the line 37, the valves 35 and 38 being closed. The compressor is then operated and withdraws gaseous refrigerant from the evaporator and forces it into the receiver. In a given apparatus the compressor will pump gaseous refrigerant at a definite rate. This rate may be, of course, influenced by the temperature and consequently the density of the gas in the evaporator, but it is found that

thruout the range of ordinary operating conditions this rate may be considered constant for practical purposes. The compressor is then operated the required length of time to 5 remove from the evaporator, condense and force into the receiver the desired reserve quantity of refrigerant. This is measured simply by timing the operation of the compressor. The refrigerant pumped into the receiver can not flow back into the evaporator because the valve 35 is closed. The compressor reduces the pressure within the evaporator and conduit 24, to some value below the pressure existing in the container 40, for example 10 to 10 pounds per square inch, gauge. The valves 36 and 38 are now opened. Refrigerant flows from the container thru the conduit 24 into the evaporator until it raises the float and closes the entrance to the evaporator. When 15 this occurs no more refrigerant can enter the system from the container 40, the evaporator contains its normal quantity of refrigerant, and the desired reserve has been accumulated in the reservoir 23. The valve 38 can then 20 be closed and the container removed, if desired. When the valve 38 has been closed the valve 35 may be opened and the system operated in its normal manner.

As a modification of the above described 30 procedure the valve 38 may be left open while the compressor is running to pump the reserve from the evaporator into the receiver. The compressor will pump at the same rate as if the valve were closed and the refrigerant 35 can flow into the evaporator as fast as the float valve will permit it.

In Fig. 2 I have shown one form of structural arrangement of the valves 35, 36 and 38. In this figure, 24' indicates the portion 40 of the conduit 24 which connects with the bottom of the receiver. Connected to the pipe 24' by any suitable means such as a nipple 50, is a fitting which includes a housing or casing 51 having a valve chamber 52 and passageways 53, 54 and 55 leading into the valve chamber. A valve stem 56 is threaded into the casing as at 57, and carries a head 58 on which are formed the two valves 35 and 36 indicated diagrammatically in Fig. 50 1. The valves co-operate with seats 35' and 36' to close the passages 53 and 55 respectively. The passage 54 communicates with a chamber containing a strainer 60 and leading to the conduit 24. The passage 55 is 55 threaded to receive a fitting 61 containing the shut-off valve 38 and the branch connection 37 which receives the conduit 39 connected to the container 40. From the foregoing it will be appreciated that when the valve 60 stem 56 is in its upper position, as shown in Fig. 2, valve 35 is open and valve 36 closed, which permits communication between the receiver 23 and evaporator 25, and prevents communication between the drum 40 and the 65 evaporator. This is the position of the valve

during normal operation of the refrigerating system. In this position it is immaterial whether the valve 38 is open or closed, the valve 38 being provided to close the conduit 37 whenever the valve 36 is open. When the 70 stem 56 is in its lower position, it will be seen that the valve 36 is open and the valve 35 seated to shut off communication between the receiver and evaporator as well as between the receiver and the container connection 37. Whenever the valve 35 is seated, the valve 38 75 may be opened to admit refrigerant from the container.

The above described fitting also provides a simple means for testing the system to ascertain whether there is any liquid in the receiver. Under certain conditions the receiver may be empty notwithstanding the fact that no hissing noise can be heard at the float valve. A test for this condition is as follows: 80 With the container 40 disconnected, close the shut-off valve 70 which is ordinarily provided at the evaporator end of the conduit 24; turn the valve stem 56 until the valve head 58 is in its mid position that is, with valves 35 85 and 36 both open; open the valve 38 slightly. If there is liquid present in the receiver liquid will flow from valve 37, but if the receiver is empty, gas will emerge, indicating that the reserve is exhausted and that the 90 system needs charging.

While the form of embodiment of the present invention as herein disclosed, constitutes a preferred form, it is to be understood that other forms might be adopted, all coming 100 within the scope of the claims which follow.

What is claimed is as follows:

1. Refrigerating apparatus comprising an evaporator, a compressor, a condenser, conduits connecting said evaporator, compressor and condenser in a closed circuit in the order named, means for closing the conduit between the condenser and evaporator, means for closing the entrance to the evaporator in response to the quantity of liquid refrigerant in the evaporator, and means between said two closing means for admitting a supply of liquid refrigerant.

2. Refrigerating apparatus comprising an evaporator, a compressor, a condenser, conduits connecting said evaporator, compressor and condenser in a closed circuit in the order named, means for closing the conduit between the condenser and evaporator, a container for liquid refrigerant, and a connection between a point below the level of liquid in said container and a point between said closing means and the evaporator.

3. Refrigerating apparatus comprising an evaporator, a compressor, a condenser, conduits connecting said evaporator, compressor and condenser in a closed circuit in the order named, means for closing the entrance to the evaporator in response to the quantity of liquid refrigerant in the evaporator, means

for closing the conduit between the condenser and evaporator, a container for liquid refrigerant, and a connection between a point below the level of liquid in said container and a point between said closing means and the evaporator.

In testimony whereof I hereto affix my signature.

FRANK W. ANDREWS.
